MARKING APPARATUS

Francis C. Worth, Ridgewood, N.Y., assignor to Adolph Gottscho, Inc., Hillside, N.J., a corporation of New York

Filed Feb. 20, 1962, Ser. No. 174,479

12 Claims. (Cl. 101—35)

This invention relates generally to a marking apparatus, and more particularly is directed to improvements in marking apparatus of the type intended to apply inked markings to vertically disposed surfaces of successive boxes, cartons or the like conveyed along a horizontal path past the marking apparatus.

In a marking apparatus of the described type, the inked markings are applied to vertical surfaces of the successive, horizontally conveyed boxes, cartons or the like by a die wheel rotating about a vertical axis and having marking means mounted on the periphery thereof for rolling contact with the surfaces to be marked. In such an apparatus, difficulty has been experienced in obtaining the uniform application of ink to the type, logotype or other marking means carried by the die wheel, particularly when such marking means extends a substantial vertical or axial distance along the die wheel or when pigmented or other quick-drying inks are employed so that the same cannot be conveniently applied through the absorbent felt pad of an ink fountain roller. Although an inking system has been provided for uniformly inking the marking means in a marking apparatus of the described character, for example, as in United States Letters Patent No. 2,655,103, issued October 13, 1953, to Malcolm Hirshey, such inking system, particularly as embodied in the structural arrangement disclosed in the foregoing patent, can only be cleaned with considerable difficulty, and does not permit rapid changes in the colors of the ink employed for the marking operation.

Further, the marking apparatus disclosed in the above identified patent must be driven in accurately timed relation to the movement of the conveyed boxes, cartons or the like, and the latter must be uniformly spaced apart along the conveyor path. It is also necessary, in such existing marking apparatus, to employ a die wheel having a circumference which corresponds to the distance along each surface to be marked and to the spacing between the successive boxes, cartons or the like on the conveyor. In addition to the above operational inflexibility of the above described existing marking apparatus, the latter is relatively costly to produce and maintain.

Accordingly, it is an object of this invention to provide a marking apparatus of the described character, that is, an apparatus adapted to apply inked markings to vertical surfaces of successive boxes, cartons or the like conveyed horizontally past the marking apparatus, and which avoids the above disadvantages of the existing marking apparatus intended for that purpose.

A more specific object is to provide a marking apparatus of the described character with an improved inking system that readily permits the thorough cleaning thereof and also facilitates changing of the color of the ink employed for the marking operation.

The accordance with an aspect of this invention, a marking apparatus of the described character is provided with an inking system in the form of a self-contained, readily removable unit adapted to be mounted adjacent a die wheel rotatable about a vertical axis and having a base constituting an ink reservoir, an inking roller and a metering roller mounted on the base for rotation about vertical axes in rolling contact with each other, an ink pump also mounted on the base and operative to draw ink from the ink reservoir and to spray such ink against

2

the inking roller adjacent the upper end of the latter, and a drive assembly for simultaneously operating the ink pump and rotating the inking and metering rollers so that the ink sprayed against the inking roller is uniformly transferred to the surface of the metering roller which, in turn, uniformly applies the ink to the marking means on the die wheel during rotation of the latter.

Since the inking system is in the form of a self-contained, readily removable unit, such unit can be detached from the remainder of the marking apparatus to permit thorough cleaning thereof, or to facilitate a rapid change in the color of the ink employed by replacing the removed unit with another identical unit containing the desired differently colored ink.

A further specific object of the invention is to provide a marking apparatus of the described character in which the drive of the die wheel and the circumference of the latter may be independent of the advancement and spacing of the conveyed boxes or cartons.

In accordance with another aspect of the invention, the die wheel is yieldably urged to rotate with a peripheral speed substantially equal to the linear speed at which the boxes, cartons or the like are conveyed past the marking apparatus, and rotation of the die wheel is arrested by a latch device which holds the die wheel at a predetermined rotational position where the marking means thereon is circumferentially spaced from both the metering roller of the inking system and the conveyed boxes, cartons or the like, so that the momentary release of the latch device by a solenoid energized through a circuit under the control of the conveyed boxes or cartons permits a single revolution of the die wheel for applying a marking to the surface of the box or carton then being conveyed past the marking apparatus and repetitive marking of the box or carton is avoided even though the dimension of the latter in the direction of its movement is greater than the circumference of the die wheel.

Another object of the invention is to provide a drive for the die wheel of a marking apparatus having the above operative characteristics, which drive is effective to continuously operate the inking system formed as a readily removable unit.

Still another object is to provide a marking apparatus of the described character which is relatively inexpensive to produce and maintain.

The above and other objects, features and advantages of the invention, will be apparent in the following detailed description of an illustrative embodiment thereof which is to be read in connection with the accompanying drawings forming a part hereof, and wherein:

FIG. 1 is a top plan view of a marking apparatus embodying this invention and being shown with its cover removed;

FIG. 2 is a side elevational view of the apparatus of FIG. 1, shown partly broken away and in section;

FIG. 3 is an end elevational view of the apparatus of FIGS. 1 and 2;

FIG. 4 is an enlarged top plan view, partly broken away and in section, of an inking unit included in the apparatus of FIGS. 1 and 2;

FIG. 5 is an elevational view of the inking unit of FIG. 4, as viewed in the direction of the arrows 5—5 on the latter;

FIG. 6 is a detail sectional view taken along the line 6—6 on FIG. 4;

FIG. 7 is a detail sectional view taken along the line 7—7 on FIG. 1;

FIG. 8 is a detail sectional view taken along the line 8—8 on FIG. 7; and

FIG. 9 is a detail view illustrating a switch arrangement by which operation of the marking apparatus is controlled.

Referring to the drawings in detail, and initially to FIGS. 1 and 2 thereof, it will be seen that a marking apparatus embodying the present invention, and there generally identified by the reference numeral 10, includes an elongated, generally flat base or support member 12 having an upstanding, vertically bored boss 14 at one end (FIGS. 2 and 3) which received and is turnable on a vertical post 16. The post 16 may be adjustably mounted in a bracket 18 (FIG. 2) which is suitably secured to the frame of the conveyor carrying the successive boxes, cartons or the like which are to be marked. The base or support member 12 is arranged to extend pivotally from post 16 alongside the path of the conveyed boxes or carton in the direction of movement of the latter, and a spring assembly indicated generally at 20 (FIGS. 2 and 3) is provided between base 12 and post 16 to urge the base to pivot in the direction moving the end of base 12 remote from boss 14 laterally toward the path of the conveyed boxes or cartons. The spring assembly 20 preferably also embodies an adjustable stop arrangement (not shown) for limiting the spring urged pivotal movement of base 12.

Adjacent its end remote from boss 14, base 12 carries an upstanding, vertical axle 22 on which a removable die wheel assembly 24 is rotatably mounted. As shown particularly in FIG. 7, the die wheel assembly 24 includes a hollow cylindrical core 26 having a bottom wall 28 formed with a central, vertically bored boss 30, and a circular cover 32 secured in the upper portion of cylindrical core 26 and having a central opening, with the central opening of cover 32 and boss 30 receiving bearings 34 and 36 by which the core 26 is rotatably mounted on axle 22. The bottom core 26 is formed with an outwardly directed radial flange 38, and the upper end of body or core 26 is provided with internal threads 40 above the core cover 32 to receive a correspondingly threaded portion 42 of a die wheel cover 44.

The die wheel cover has an annular recess in which is mounted a ring 45 of frictional material and a bearer rim 46, which comprise a slippable clutch assembly, the function of which will hereinafter be described. The die wheel cover further acts to hold a retaining or spacer ring 48 on the upper end of core 26. The marking means, for example, in the form of rubber type or logotype 50 mounted adhesively on a metal backing plate 52, is secured on the outer surface of body or core 26 between flange 38 and spacer ring 48 so that such marking means can be conveniently removed or exchanged merely by loosening die wheel cover 44 with respect to core 26. The die wheel assembly 24 is conveniently retained on axle 22 by means of a knurled nut 54 screwed on a threaded extension 56 at the upper end of axle 22 and engageable axially against the flanged upper end of the bearing 34 carried by core cover 32. Thus, the entire die wheel assembly 24 can be conveniently removed as a unit for replacement by a similar die wheel assembly having different type elements or marking means thereon when the marking to be applied is changed, or when a different colored ink is to be employed.

Mounted on the lower end portion of axle 22 below die wheel assembly 24 is a bearing 58 which carries a rotatable drive sprocket 60 and a bearer and clutch plate assembly generally identified by the reference numeral 62, and which is hereinafter described in detail. The drive for the sprocket 60 includes an endless chain 64 (FIG. 1) running around sprocket 60 and also around a sprocket 66 (FIGURE 3) which is secured on the lower end portion of a shaft 68 extending vertically alongside boss 14 and having its lower and upper ends respectively journalled in bearings carried by the base 12 and by a bearing support bracket 70 which projects radially from, and is secured to post 16 above boss 14. Shaft 68 is rotatably driven by meshing engagement of a spur gear 72 secured thereon with a spur gear 74 rotatable on post 16 above bearing support bracket 70. Spur gear 74 is inte-

gral, or otherwise rotatably coupled with a bevel gear 76 which meshes with a bevel gear 78 (FIGS. 1 and 3) forming part of a rotatable drive shaft assembly 80. The drive shaft assembly 80 extends horizontally and laterally with respect to the direction of movement of the conveyed boxes or cartons, and includes a sprocket 82 driven through a chain 84 from a suitable electric drive motor (not shown) or from a driven shaft of the associated box or carton conveyor. The drive shaft assembly 80 has a shaft 86 with its opposite ends supported in a fixed bracket 88 and in a socket at the upper end of post 16, and a sleeve 90 rotatable on shaft 86 and having both the bevel gear 78 and the sprocket 82 secured thereon, as by set screws, so as to form a driving connection therebetween.

The chain 64, which connects sprocket 66 with drive sprocket 60 for the die wheel, is engaged by a tensioning idler sprocket 92 (FIG. 1) which is freely rotatable on an arm 94 adjustably pivoted, as at 96, on the base 12. The chain 64 further runs around a sprocket 98 (FIG. 5) which is freely rotatable on a stub axle 100 projecting upwardly from base 12. The sprocket 98 has a hub 102 which is formed, as hereinafter described in detail, to provide a releasable drive coupling for an inking unit generally identified by the reference numeral 104.

The inking unit 104 (FIGS. 1, 2, 4 and 5) includes a hollow, upwardly opening base 106 defining an ink reservoir 108 (FIG. 6) and having a removable cover plate 110 extending over a portion of the reservoir. Posts 112 project upwardly from the hollow base 106 and, at their upper ends, support a top plate 114. A vertical drive shaft 116 has its upper end journalled in a bearing carried by top plate 114, while the lower end of shaft 116 extends downwardly through, and is journalled in a corner projection 118 of body 106. The lower end of shaft 116 is adapted to extend downwardly into an upwardly opening socket 120 (FIG. 5) formed in the hub 102 of sprocket 98, and carries a diametrically extending pin 122, the ends of which are engageable in upwardly opening notches formed in the hub 102. Thus, when the lower end of shaft 116 is engaged in socket 120, the engagement of pin 122 in the above mentioned notches provides a rotatable coupling between sprocket 98 driven by chain 64 and the drive shaft 116 of inking unit 104.

The base 106 of inking unit 104 further has a lug 124 (FIGS. 1 and 4) extending from the end thereof remote from projection 118 and having an arcuate slot 126 concentric with the axis of shaft 116 and adapted to receive a locking screw 128 which extends into a tapped hole in the base or support member 12 of the marking apparatus. Thus, the inking unit 104 is adjustably secured on base 12 by engagement of the lower end of drive shaft 116 in the socket 120 of sprocket 98 and by the engagement of screw 128 in the slot 126 of lug 124, and the inking unit can be angularly adjusted about the axis of drive shaft 116 upon loosening of the screw 128.

In accordance with the present invention, the inking unit 104 further includes an ink supplying or inking roller 130 and a metering or ink transferring roller 132 mounted for rotation about substantially vertical axes in suitable upper and lower bearings (not shown) carried by the top plate 114 and the base 106, respectively (FIGS. 2, 4 and 5). The ink transferring or metering roller 132 is disposed so that its surface is adapted for rolling contact with the marking means 50 on die wheel 24 during rotation of the latter, while the inking roller 130 is disposed for rolling contact with metering roller 132 at a location on the latter which is substantially diametrically opposed with respect to the location of the contact of roller 132 with the marking means.

In order to effect rotation of rollers 130 and 132, the inking unit 104 includes an endless chain 134 (FIGS. 4 and 5) running around a sprocket 136 fixed on the upper end portion of drive shaft 116 and around a sprocket 138 fixed on the shaft of metering roller 132 above the latter.

The rotation of metering roller 132 is transmitted to inking roller 130 by means of a spur gear 140 fixed on the shaft of roller 132 above sprocket 138 and meshing with a spur gear 142 fixed on the shaft of roller 130 above the latter. A tensioning idler sprocket 144 is rotatable on a stub shaft 146 depending from top plate 114 and engages the chain 134 between sprockets 136 and 138 in order to maintain the necessary tension in that drive chain.

In order to supply ink to the surface of inking roller 130, the inking unit 104 further includes a pump assembly 148 having a housing 150 secured on top of cover plate 110 by a screw 152. The housing 150 is formed with a longitudinal blind bore 156 (FIG. 6) into which a pump plunger 158 slidably extends. The outer end of bore 156 is sealed around plunger 158 by a gland nut and packing 160, and a helical spring 162 is preferably disposed between the inner ends of bore 156 and plunger 158 to urge the latter to project axially from the bore. The pump assembly 148 further includes an inlet tube 164 depending from housing 150 through an opening in cover plate 110 into the ink reservoir 108. The inlet tube 164 contains a ball check valve 166 permitting flow therethrough only in the upward direction from ink reservoir 108 into the inner end of bore 156. An outlet tube 168 projects upwardly from housing 150 and contains a ball check valve 170 which permits flow therethrough only in the upward direction from the inner end of bore 156 through a flexible plastic or rubber tube 172 extending, at its lower end, onto outlet tube 168.

The hole in cover plate 110 through which inlet tube 164 extends is disposed so that screw 152 and tube 164 locate housing 150 with the longitudinal axis of bore 156 and plunger 158 passing substantially through the axis of drive shaft 116, as is apparent in FIG. 4. A radial cam 174 (FIGS. 4 and 5) is secured on the lower end portion of shaft 116 for engagement, at its periphery, with the outer end of plunger 158. It will be apparent that the outer end of plunger 158 is maintained in engagement with the periphery of radial cam 174 by spring 162, and that rotation of the cam with shaft 116 will effect reciprocation of plunger 158 for pumping ink from reservoir 108 through flexible tube 172.

The supply of ink in reservoir 108 may be replenished through an opening 176 (FIG. 4) in cover plate 110, for example, from an inverted bottle or other receptacle 178 (FIG. 1) having its neck secured in opening 176 by a thumb screw 180 (FIG. 4).

The flexible tube 172 carrying ink from pump assembly 148 is connected, at its upper end, to a hose fitting 182 opening through a substantially semi-cylindrical shield 184 (FIGS. 2 and 4) extending partly around inking roller 130. Shield 184 has a lip or rim 186 at its upper end by which the shield 184 is suspended from top plate 114, as by screws 188. The hose fitting 182 is vertically disposed along shield 184 so as to open against the surface of roller 130 at a location adjacent the upper end portion of the latter.

A splash plate 185 (FIGS. 1 and 2) is suitably secured on inking unit 104 at the side of the latter facing toward the path of the conveyed boxes or cartons to prevent splashing of ink onto the latter from the rotated rollers 130 and 132.

It will be apparent that, when the above described inking unit 104 is installed in its illustrated operative position on base 12 and its shaft 116 is rotated through drive chain 64 and sprocket 98, the rollers 130 and 132 are rotated and the pump assembly 148 is simultaneously operated to pump ink from reservoir 108 for sprayed discharge against the surface of rotated inking roller 130. Due to the influence of gravity, the ink sprayed against the upper portion of roller 130 tends to flow downwardly along the latter and, by reason of the rolling contact of rollers 130 and 132, ink is applied uniformly from roller 130 to the surface of the metering or ink transferring roller 132. Any excess of ink dripping from the lower ends of

rollers 130 and 132 is returned to reservoir 108 so that a continuous circulation of ink is maintained to permit the use of pigmented or other quick drying inks.

Since the inking unit 104 of the marking apparatus 10 embodying this invention is quickly removable from the base 12 merely by loosening of the screw 128 and disengagement of the latter from slot 126, it is apparent that the inking unit may be readily removed for thorough cleaning thereof, or when it is desired to replace the inking unit with an identical unit containing ink of a different color.

It will also be apparent that the previously described angular adjustment of inking unit 104 about the axis of its drive shaft 116 is effective to vary the position of the metering or ink transferring roller 132 with respect to the axis of die wheel assembly 24, either for adjusting the contact pressure of roller 132 with the marking means 50 or for accommodating die wheels of different diameters, such adjustment being facilitated by a turnable eccentric 139 (FIG. 1) engaging lug 124.

In accordance with the present invention, inking unit 104 may be continuously operated, while the die wheel assembly 24 is intermittently rotated through a single revolution only upon movement of a conveyed box or carton past the die wheel assembly. More specifically, as shown on FIG. 8 of the drawings, the foregoing purpose is served by providing the flange 38 at the bottom of die wheel core 26 with an inwardly tapering portion, as at 190, to define a radial shoulder 192 facing in the direction of the intended rotation of the die wheel assembly indicated by the arrow 194. A latch 196 is pivotally mounted, at one end, on a screw 198 threaded into a post 200 projecting from the base or support member 12 of the marking apparatus adjacent die wheel assembly 24, and latch 196 is formed, intermediate its ends, with a nose 202 adapted for engagement with shoulder 192 for holding the die wheel core 26 against rotation. A torsion spring 204 may be provided between post 200 and latch 196 for urging the latter to rock or pivot in the direction moving nose 202 against the periphery of flange 38. The free end of latch 196 is pivotally connected, as at 206, to the armature 208 of a solenoid 210 which is suitably secured, as by screws 212, on the base 12 of marking apparatus 10. The solenoid 210 is arranged to retract its armature 208, and thereby release the nose 202 of the latch from the shoulder 192, upon energization of the solenoid. Thus, the die wheel assembly is freed for rotation about axle 22 whenever solenoid 210 is energized.

As represented diagrammatically on FIG. 1, the electrical circuit for energizing solenoid 210 includes a source 214 of electric current and conductors 216 connecting such source to the coil of solenoid 210 and having a normally open switch 218 interposed therein so that solenoid 210 is energized only upon closing of switch 218. In the marking apparatus 10 embodying this invention, the closing of switch 218 for energizing solenoid 210, and thereby permitting rotation of the die wheel assembly, is controlled by the successive boxes or cartons conveyed past the marking apparatus so that the drive of the marking apparatus through the chain 84 need not be accurately synchronized with the advancement of the conveyed boxes or cartons.

As shown in FIG. 9, the switch 218 may be of the type commonly known as a microswitch having a rockable projecting actuating finger 220 which is shown in its switch-open position, and which is adapted to close the contacts of switch 218 upon rocking of finger 220 from that position. An extension 222 is pivoted on finger 220, as at 224, and is rockable relative to the latter from the illustrated position only toward the right or in the counter-clockwise direction about pivot 224. An actuating lever 226 is pivotally mounted intermediate its ends, as at 228, adjacent the path of travel of the conveyed boxes or cartons at a location following the die wheel assembly 24 considered in the direction of advancement of the con-

veyor indicated by the arrow 230 on FIG. 9. A spring 232 yieldably urges the actuating lever 226 to the position shown in full lines where the actuating lever engages a stop pin 234 and has one of its ends 226a projecting laterally into the path of travel of the conveyed boxes or cartons. Thus, when the front corner of a conveyed box or carton reaches the location of actuating lever 226, the end 226a of the lever is engaged by that corner and the lever is rocked to the position shown in broken lines at 226'. The switch 218 is mounted in relation to lever 226 so that, during rocking of the lever from the normal position shown in full lines to the rocked position shown in broken lines, the end 226b of the lever acts against the extension 222 of the switch actuating finger 220 to rock the latter and thereby cause momentary closing of the contacts of switch 218 and consequently momentary energization of solenoid 210 so as to release latch 196 and permit rotation of the die wheel assembly 24.

When the trailing end of a marked box or carton releases lever 226 so that the latter can be rocked back to its normal position by the spring 232, the engagement of the end 226b of the lever with the extension 222 during such return rocking movement of the lever merely causes angular displacement or pivoting of extension 222 relative to actuating finger 220 so that the latter remains stationary and closing of the switch contacts does not then occur.

From the above it will be apparent that solenoid 210 is momentarily energized to release latch 196 as the leading end of each conveyed box or carton reaches a predetermined position beyond die wheel assembly 24, as determined by the location of lever 226 along the path of the conveyed boxes or cartons. Upon release of the latch 196, the slippable clutch assembly 45, 46 and the bearer and clutch plate assembly 62 and the rotated sprocket 60 effect a single complete revolution of the die wheel core 26 and, since solenoid 210 is only momentarily energized, as indicated above, latch 196 has its nose 232 urged against the periphery of flange 38 to again engage the shoulder 192, and thereby prevent further rotation of die wheel core 26 at the completion of the single revolution.

As shown particularly in FIG. 7, the bearer and clutch plate assembly 62 includes a circular plate 236 mounted, at its center, for rotation on the bearing 58 and having a bearer rim 238 of rubber or other resilient frictional material on its periphery for frictional engagement with the side surface of each conveyed box or carton as the latter passes the die wheel assembly. Further, clutch elements 240 and 242, which may be in the form of disks of friction material, are cemented, or otherwise secured on the top and bottom surfaces, respectively, of circular plate 236 for frictional engagement with the bottom wall 28 of die wheel core 26 and with the rotatably driven sprocket 60. Thus, a slippable rotatable coupling is provided between the rotatably driven sprocket 60 and the plate 236 of bearer and clutch plate assembly 62, and between plate 236 and die wheel core 26. By reason of the above rotatable coupling, bearer and clutch plate assembly 62 tends to rotate die wheel core 26 either in response to frictional engagement of the bearer rim 238 with a conveyed box or carton or by transmission of rotation from rotated sprocket 60, but rotation of the die wheel core 26 can occur only upon release of latch 196, as previously described in detail. When rotation of die wheel core 26 is arrested by engagement of latch 196 with the shoulder 192 on the die wheel core, slippage occurs between the bottom wall of the die wheel core and the frictional clutch elements 240 and between the frictional clutch elements 242 and sprocket 60, as well as between the slippable clutch assembly 45, 46.

In the marking apparatus 10, the marking means 50 are circumferentially arranged on the periphery of die wheel core 26 in relation to the position of shoulder 192 so that, when shoulder 192 is engaged by latch 196, mark-

ing means 50 faces away from both the path of the conveyed boxes or cartons and the ink transferring or metering roller 132 of inking unit 114. Thus, die wheel core 26 can be held against rotation by engagement of latch 196 with shoulder 192 while a box or carton passing the die wheel assembly 24 engages bearer rims 45 and 238 without causing blurring or smearing of ink from the marking means 50 onto the conveyed box or carton, and the inking unit 114 can be continuously operated to permit the use of quick drying inks without causing excessive build-up of ink on the marking means 50 during such period when die wheel core 26 is held against rotation.

The apparatus 10 may further be provided with a removable cover 244 mounted on base 12 to extend over inking unit 114 and the components of the drive on the base.

Although the operation of each of the component parts of marking apparatus 10 has been described in detail hereinabove, the overall operation of the apparatus is summarized, as follows:

With the chain 34, and hence the chain 64, being continuously driven, the inking unit 114 mounted on base 12 is continuously operated and the sprocket 60 is continuously rotated. However, the normal engagement of the latch 196 with shoulder 192 of die wheel core 26 holds the latter against rotation even during the movement of the forward portion of a conveyed box or carton past the die wheel assembly 24 to frictionally effect rotation of the bearer rims 45 and 238. When the forward end of the conveyed box or carton engages the actuating lever 226, and thereby effects momentary closing of switch 218 and energization of solenoid 210, latch 196 is released to permit rotation of die wheel core 26 through the positive drive by rotated sprocket 60 and the frictional drive of bearer rim 238 of assembly 62 and bearer rim 45 of the slippable clutch assembly 45, 46 upon engagement with the conveyed box or carton. Thus, die wheel core 26 is turned through a single complete revolution to cause marking means 50 to pass the ink transferring or metering roller 132 of inking unit 114, and thereby receive ink from the latter, and then to move into rolling and marking contact with the adjacent side surface of the conveyed box or carton. Since the die wheel core 26 is driven from bearer and clutch plate assembly 62 and the slippable clutch assembly 45, 46 in frictional engagement with the conveyed box or carton during marking of the latter, the peripheral speed of movement of the marking means 50 is exactly equivalent to the linear speed of the conveyed box or carton, thereby to avoid blurring of the inked impression applied to the box or carton.

Since the release of the latch 196 is controlled by the position of each conveyed box or carton to be marked in relation to the location of the die wheel assembly 24, it will be apparent that the location of the inked impression applied to each of the conveyed boxes or cartons will be uniform, without regard to the speed of advancement of the conveyed boxes or cartons or the spacing therebetween on the conveyor.

If the length of the conveyed box or carton in the direction of the movement thereof exceeds the circumference of die wheel assembly 24, so that die wheel core 26 is returned to its initial position where latch 196 again engages shoulder 192 at a time when bearer rims 45 and 238 are still frictionally engaged by the conveyed box or carton, then latch 196 arrests rotation of die wheel core 26 and the bearer rims can continue to rotate with respect thereto by reason of the slippable mounting of rim 45 and the slippable coupling between assembly 62 and core 26. On the other hand, if the circumference of the die wheel assembly 24 exceeds the length of the conveyed box or carton in the direction of movement of the latter, so that the conveyed box or carton moves out of engagement with bearer rim 238 prior to the return of die wheel core 26 to its original position where

latch 196 again engages shoulder 192, then the rotated sprocket 68 is effective, through the slippable rotational coupling formed by the assembly 62, to cause the further rotational movement of die wheel core 26 necessary to return the latter to the original position.

From the above it is apparent that, in the marking apparatus 10 embodying this invention, the diameter of die wheel core 26 need not be related to the dimensions of the successive conveyed boxes or cartons or the spacing therebetween on the conveyor, and further that the drive of the marking apparatus need not be correlated to the advancement of the conveyed boxes or cartons in order to ensure the uniform application of inked impressions to the latter.

It will also be apparent that the described drive of the die wheel assembly 24 is achieved with a structure that readily permits the upward removal of the die wheel core 26 from its supporting axle 22, and thereby facilitates either changing of the marking means on the die wheel assembly or interchange of the latter with a similar die wheel assembly intended for use with ink of a different color.

Although an illustrative embodiment of the invention has been described in detail herein with reference to the accompanying drawings, it is to be noted that the invention is not limited to that precise embodiment, and that various changes and modifications may be effected therein by one skilled in the art without departing from the scope or spirit of the invention, except as defined in the appended claims.

What is claimed is:

1. An apparatus for marking vertical surfaces of articles, such as boxes or cartons, conveyed horizontally past the apparatus, comprising:
  - (a) Supporting means adapted to be disposed along- side the path of travel of the conveyed articles;
  - (b) A die wheel assembly mounted on said supporting means for rotation about a vertical axis and including
    - (1) a die wheel core adapted to carry marking means on the periphery thereof,
    - (2) bearer means turnable by frictional engage- ment with a conveyed article passing said die wheel assembly, and
    - (3) slippable coupling means urging said die wheel core to rotate with said bearer means;
  - (c) Drive means including a rotated drive member coaxial with said die wheel assembly and slippable coupling means urging said die wheel core to rotate with said rotated drive member;
  - (d) Latch means normally holding said die wheel core against rotation at an original position where the marking means thereon faces away from the path of the conveyed articles and being releasable to permit rotation of said die wheel core through said bearer means and said rotated drive member;
  - (e) Means operative to release said latch means and thereby permit rotation of said die wheel core through a single complete revolution from said original position when a conveyed article moves to a predetermined location with respect to said die wheel assembly; and
  - (f) An inking unit removably mounted on said sup- porting means and operated continuously from said drive means to apply ink to the marking means on said core only upon rotation of the latter.
2. An apparatus for marking vertical surfaces of articles, such as boxes or cartons, conveyed horizontally past the apparatus, comprising:
  - (a) Supporting means adapted to be disposed along- side the path of travel of the conveyed articles;
  - (b) A die wheel assembly mounted on said supporting means for rotation about a vertical axis and including
    - (1) a die wheel core adapted to carry marking means on the periphery thereof,
    - (2) bearer means turnable by frictional engage- ment with a conveyed article passing said die wheel assembly,

ment with a conveyed article passing said die wheel assembly, and

- (3) slippable coupling means urging said die wheel core to rotate with said bearer means;
- (c) Drive means including a rotated drive member coaxial with said die wheel assembly and slippable coupling means urging said die wheel core to rotate with said rotated drive member;
- (d) Latch means normally holding said die wheel core against rotation at an original position where the marking means thereon faces away from the path of the conveyed articles and being releasable to permit rotation of said die wheel core through said bearer means and said rotated drive member;
- (e) Means operative to release said latch means and thereby permit rotation of said die wheel core through a single complete revolution from said original position when a conveyed article moves to a predetermined location with respect to said die wheel assembly; and
- (f) An inking unit removably mounted on said sup- porting means and including
  - (1) at least one roller rotatable about a vertical axis and positioned for rolling contact with marking means on said die wheel core upon rotation of the latter from said original position,
  - (2) a source of ink,
  - (3) means operative to apply ink from said source to the surface of said roller for transfer from the latter to the marking means, and
  - (4) means engageable with said drive means when the inking unit is mounted on said supporting means to continuously operate said ink applying means and rotate said roller so that quick-drying inks can be employed in the inking unit.
3. An apparatus for marking vertical surfaces of articles, such as boxes or cartons, conveyed horizontally past the apparatus, comprising:
  - (a) Supporting means adapted to be disposed alongside the path of travel of the conveyed articles;
  - (b) A die wheel assembly mounted on said supporting means for rotation about a vertical axis and including
    - (1) a die wheel core adapted to carry marking means on the periphery thereof,
    - (2) bearer means turnable by frictional engage- ment with a conveyed article passing said die wheel assembly, and
    - (3) slippable coupling means urging said die wheel core to rotate with said bearer means;
  - (c) Drive means including a rotated drive member coaxial with said die wheel assembly and slippable coupling means urging said die wheel core to rotate with said rotated drive member;
  - (d) Latch means normally holding said die wheel core against rotation at an original position where the marking means thereon faces away from the path of the conveyed articles and being releasable to permit rotation of said die wheel core through said bearer means and said rotated drive member;
  - (e) Means operative to release said latch means and thereby permit rotation of said die wheel core through a single complete revolution from said original position when a conveyed article moves to a predetermined location with respect to said die wheel assem- bly; and
  - (f) An inking unit removably mounted on said sup- porting means and including
    - (1) an ink transferring roller rotatable about a vertical axis and positioned for rolling contact with marking means on said die wheel core upon rotation of the latter from said original position,
    - (2) an inking roller in rolling contact with said ink transferring roller,
    - (3) a source of ink,
    - (4) pump means operative to apply ink from said

- source to the surface of said inking roller for transfer from the latter by said ink transferring roller to the marking means, and
- (5) means engageable with said drive means when the inking unit is mounted on said supporting means to continuously operate said pump means and rotate said inking and transferring rollers so that quick-drying inks can be employed in the inking unit.
4. An apparatus for marking vertical surfaces of articles, such as boxes or cartons, conveyed horizontally past the apparatus, comprising:
- (a) Supporting means adapted to be disposed alongside the path of travel of the conveyed articles;
  - (b) A die wheel assembly mounted on said supporting means for rotation about a vertical axis and including
    - (1) a die wheel core adapted to carry marking means on the periphery thereof,
    - (2) bearer means turnable by frictional engagement with a conveyed article passing said die wheel assembly, and
    - (3) slippable coupling means urging said die wheel core to rotate with said bearer means;
  - (c) Drive means including a rotated drive member coaxial with said die wheel assembly and slippable coupling means urging said die wheel core to rotate with said rotated drive member;
  - (d) Latch means normally holding said die wheel core against rotation at an original position where the marking means thereon faces away from the path of the conveyed articles and being releasable to permit rotation of said die wheel core through said bearer means and said rotated drive member;
  - (e) Means operative to release said latch means and thereby permit rotation of said die wheel core through a single complete revolution from said original position when a conveyed article moves to a predetermined location with respect to said die wheel assembly; and
  - (f) An inking unit including
    - (1) a hollow base removably mounted on said supporting means and constituting an ink reservoir,
    - (2) first and second vertical rollers rotatably mounted on said base in rolling contact with each other and with said first roller disposed for rolling contact with marking means on said die wheel core upon rotation of the latter from said original position,
    - (3) pump means mounted on said base and operative to draw ink from said reservoir and discharge the ink against said second roller for transfer by said first roller from said second roller to the marking means, and
    - (4) means releasably engageable with said drive means when said base is mounted on said supporting means to continuously operate said pump means and rotate said rollers so that quick-drying inks can be employed in the inking unit.
5. An apparatus as in claim 4; wherein said pump means includes a housing having a bore with a valved inlet opening from said reservoir and a valved outlet opening from said bore, a conduit extending from said outlet and opening adjacent the upper portion of the surface of said second roller, and a plunger reciprocable in said bore to pump ink into the bore from said inlet and out of the bore through said outlet.
6. An apparatus as in claim 5; wherein said means releasably engageable with the drive means to operate the pump means and rotate the rollers includes a drive shaft rotated by said drive means, a cam on said drive shaft engaged by said plunger to reciprocate the latter, a sprocket and chain drive between said drive shaft and one of said rollers, and gear means rotatably connecting

- said rollers for counter rotation with respect to each other.
7. An apparatus as in claim 6; wherein said rotated drive member of the drive means is in the form of a sprocket, and said drive means further includes a driven chain running around said sprocket, an additional sprocket rotatably mounted on said supporting means and engaged by said driven chain, and releasable coupling means for connecting said additional sprocket with said drive shaft of the inking unit.
8. An apparatus for marking vertical surfaces of articles, such as boxes or cartons, conveyed horizontally past the apparatus, comprising:
- (a) Supporting means adapted to be disposed alongside the path of travel of the conveyed articles;
  - (b) A die wheel assembly mounted on said supporting means for rotation about a vertical axis and carrying marking means at its periphery for rolling and marking contact with the successive conveyed articles;
  - (c) Drive means urging said die wheel assembly to rotate and including a continuously driven chain mounted on said supporting means;
  - (d) Article actuated control means for said die wheel assembly permitting rotation of the latter through a single complete revolution in response to the movement of a conveyed article past said die wheel assembly;
  - (e) An inking unit including
    - (1) a hollow base removably mounted on said supporting means and constituting an ink reservoir,
    - (2) first and second vertical rollers rotatably mounted on said base in rolling contact with each other, with said first roller disposed for rolling contact with said marking means on the die wheel assembly upon rotation of the latter,
    - (3) pump means mounted on said base and operative to draw ink from said reservoir and discharge the ink against said second roller for transfer by said first roller from said second roller to the marking means,
    - (4) a vertical drive shaft rotatably supported by said base, and
    - (5) means operating said pump means and rotating said rollers in response to rotation of said drive shaft;
  - (f) A sprocket mounted on said supporting means and being rotatably driven by said chain; and
  - (g) Axially releasable coupling means on said drive shaft and sprocket, respectively, engageable upon mounting of said inking unit on said supporting means.
9. An apparatus as in claim 8; further comprising means for securing said base on said supporting means including a lug extending from said base and having an arcuate slot concentric with the axis of said drive shaft, and a locking screw receivable in said slot and threaded into said supporting means so that loosening of said screw permits angular adjustment of said base about said axis of the drive shaft for varying the pressure of contact of said first roller with said marking means.
10. An apparatus for marking vertical surfaces of articles, such as boxes or cartons, conveyed horizontally past the apparatus, comprising:
- (a) Supporting means adapted to be disposed alongside the path of travel of the conveyed articles and carrying an upstanding vertical axle;
  - (b) A die wheel assembly including
    - (1) a cylindrical die wheel core slidable downwardly on said axle and adapted to carry marking means on the periphery thereof,
    - (2) bearer means on said axle below said core and being turnable by frictional engagement with a conveyed article passing said die wheel assembly, and

- (3) frictional clutch elements on the top of said bearer means urging said die wheel core to rotate with said bearer means;
- (c) Drive means including a rotated sprocket on said axle below said bearer means and frictional clutch elements on the bottom of the latter for urging said bearer means and said die wheel core to rotate with said rotated sprocket;
- (d) Latch means normally holding said die wheel core against rotation at an original position where the marking means thereon faces away from the path of the conveyed articles and being releasable to permit rotation of said die wheel core through said bearer means and said rotated sprocket;
- (e) Means operative to release said latch means and thereby permit rotation of said die wheel core through a single complete revolution from said original position when a conveyed article moves to a predetermined location with respect to said die wheel assembly; and

20

- (f) An inking unit removably mounted on said supporting means and operated continuously from said drive means to apply ink to the marking means on said core only upon rotation of the latter.
- 5 11. An apparatus as in claim 10; wherein said die wheel assembly is removably mounted on said axle to permit removal thereof as a unit.
- 10 12. An apparatus as in claim 10; wherein said marking means is removably mounted on said die wheel core, and including a removable die wheel cover to permit the removal of said marking means from said core.
